UNITED STATES PATENT OFFICE.

RICHARD H. WESTERFIELD, OF KENTON, OHIO.

DESIGN FOR A RANGE.

SPECIFICATION forming part of Design No. 36,006, dated August 12, 1902.

Application filed June 6, 1902. Serial No. 110,556. Term of patent 3½ years.

To all whom it may concern:

Be it known that I, RICHARD H. WESTERFIELD, a citizen of the United States, residing at Kenton, in the county of Hardin and State of Ohio, have invented and produced a new, original, and ornamental Design for Ranges, of which the following is a specification, reference being had to the accompanying drawings, forming part thereof.

10 The figure is a perspective view of a range, showing my new design. The range has a plain top and base of usual appearance and has immediately below the plain base an ornamental subbase 2, having 15 curved outlines continuous with the similar outlines of the legs. Above the top is an ornamental support for shelves, said support having curved outlines. The range has a

hearth 4, also provided with curved outlines, and these several parts and an extension and 20 the doors 3 are provided with ornamental surfaces comprising the approximately circular foliations 1 and constitute the leading feature of my new design.

Having described my invention, what I 25 claim as new, and desire to secure by Letters Patent, is—

The ornamental design for a range, as herein shown and described.

In testimony whereof I have signed my 30 name to this specification in the presence of two subscribing witnesses.

RICHARD H. WESTERFIELD.
